HAIR CURLER

Carl E. Anderson, East Orange, N. J., assignor to
Eastern Tool & Mfg. Co., Bloomfield, N. J.

Application June 19, 1936, Serial No. 86,038

5 Claims. (Cl. 132—33)

This invention relates to an improved hair curler of the type that is rolled inside a curl and, having an open end, a hairpin is placed over the curl and the curler and then the curler 5 is withdrawn.

The improved curler is cheap to manufacture and is adapted to receive a strand of hair and clasp the end thereof, the curler then being clamped by a simple movement of a band which 10 is permanently on the curler. The band is also used to release the curler from clamping engagement with the hair.

The invention is illustrated in the accompanying drawing. Figure 1 is a perspective view of 15 my improved curler in open or released position. Figure 2 is a side view of the curler in closed position. Figure 3 is a side view of the curler with a curl secured thereon and illustrating how a hairpin is inserted before withdrawal of the 20 curler. Figure 4 is a section on line 4—4 in Figure 1. Figure 5 is a section on line 5—5 in Figure 2. Figure 6 is a section on line 6—6 in Figure 2.

The hair curler consists of a pair of normally 25 slightly divergent or separated tongues, an end piece and a clamping means. In the form illustrated, which is the preferred form, I show the body portion of the device made of one piece of sheet metal. The piece of metal comprises 30 an end piece 10 which connects two tongues, the tongues comprising the curlers proper 11 and a head portion 12 and a tapered portion 13. The tapered portion 13 is adjacent the end 35 piece and is reduced in diameter relative the curlers proper and the end piece in order to confine the clamping means.

The clamping means comprises a band 14, preferably of round wire, and usually completely 40 encircling the tapered portion to provide no free ends to become entangled in the hair.

One of the curlers 11 is provided with lips 15 which extend a slight distance inside the other one in order to keep the two members in opposite relation.

The tapered portion 13 which may be formed 45 on one or both tongues is broadest near the end piece which enables the device to be closed with one hand.

In using the curler the parts are in open 50 position at the start and the end of the hair to form the curl is placed in the slit 16 between the tongues. The band 14 is then slid to engage the broad end of the tapered part. This is readily done by the thumb and fingers of one hand as shown by dotted lines in Figure 2. The curler is then turned up inside the hair to form a curl on the outside of the curler, as shown in Figure 3. When the curl is fully wound a

hair pin, shown at 17, is passed with one reach inside the open end of the curler and the other outside the curl at the bottom of the curler. The band 14 is then slid to the narrower part of the tapered portion, which allows the tongues 5 to separate slightly and the curler is easily withdrawn longitudinally leaving the curl undisturbed in the grasp of the hair pin.

In order to minimize friction between the body 10 of the curler and the band by reducing the contact surfaces, the tapered part is preferably made on a smaller radius or semi-oval which makes only two points of contact at 18, as shown in Figure 5.

The curler is light in weight, is economically 15 made and is easily operated.

I claim:

1. A hair curler comprising a sheet metal body portion bent to form a transverse end, a tapered neck and a pair of parallel hair engaging 20 tongues, and a ring encircling the tapered neck.

2. A hair curler comprising body portion of a single piece of material formed into a laterally disposed end piece and longitudinally projecting 25 tongues with a normal spring action tending to hold the tongues slightly separated, at least one of the tongues being slightly tapered adjacent the end piece, and a ring encircling the tongues at the tapered portion.

3. A hair curler comprising a pair of opposed 30 tongues substantially semi-circular in cross-section, a laterally disposed end piece supporting the tongues in slightly separated relation, at least one of the tongues having a tapered portion adjacent the end piece, and a band on the tapered portion to act as means for moving the tongues toward each other.

4. A hair curler comprising a pair of opposed 40 tongues substantially semi-circular in cross-section, a laterally disposed end piece supporting the tongues in slightly separated relation, the tongues having tapered portions adjacent the end piece, the tapered portions being semi-elliptical, and a band on the tapered portion and bearing on the high points to minimize the surface of contact between the band and the said 45 tapered portions.

5. A hair curler comprising a sheet metal strip 50 bent to form an end piece and extended therefrom to form two slightly separated tongues of substantially semi-circular form in cross-section, the tongues having a reduced tapered portion adjacent the end piece, and a band on the tapered portions for slidably closing engagement therewith and of a diameter less than that of the tongues whereby the band is confined to 55 the tapered portion.

CARL E. ANDERSON.
